UNITED STATES PATENT OFFICE.

ALBERT J. SMILEY, OF PHILADELPHIA, PENNSYLVANIA.

DISH MAT.

Application filed September 16, 1922. Serial No. 588,648.

To all whom it may concern:

Be it known that I, ALBERT J. SMILEY, a citizen of the United States, residing at Philadelphia, in the county of Philadelphia and State of Pennsylvania, have invented certain new and useful Improvements in Dish Mats, of which the following is a specification, reference being had to the accompanying drawings.

10 This invention relates to mats, and more particularly to dish mats.

It is an object of the invention to provide a mat of this character adapted to be placed upon the drain board to prevent contact of 15 the dishes with the drain board.

It is another object of the invention to provide a mat of this character wherein the mat not only serves to prevent contact of the dishes with the drain board, but permits 20 the dishes to drip and permits the drippings to return to the sink unobstructedly.

It is a further object of the invention to provide a device of this character which may be readily folded when not in use, and stored 25 in a small place, and wherein the means used to connect the sections of the mat to each other are also used to prevent contact of the dishes with the frames of the mats.

With these and other objects in view, the 30 invention consists in the improved construction and arrangement of parts to be herein-after more particularly described, fully claimed and illustrated in the accompanying drawings, in which:—

35 Figure 1 is a top plan view of a dish mat constructed in accordance with an embodiment of the invention;

Figure 2 is another form of the invention; and

40 Figure 3 is a fragmentary sectional view taken on the line 3—3 of Figure 1.

Referring to the drawings, 5 and 6 designate frames, preferably rectangular, each frame consisting of a strip of material, bent 45 at its central portion to provide the end 7 of the frame and side portions 8 and 9, the end portions of the strip being extended toward each other and secured by any suitable means to provide the end 10 of the frame. It is of course obvious that any 50 number of these frames may be provided, according to the size of the drain board.

Extending longitudinally of each frame is a series of expandible and retractable supporting members 11, each member consisting 55 of a length of resilient wire coiled sub-

stantially in the form of a coil spring, the coils being partially separated. The end 12 of the member is secured to the end 10 of the frame, while the end 13 of the member 60 is secured to the end 7. This securing operation may be done by soldering said ends to the edges of the frame or inserting the ends in openings provided in the frame. Each of the members 11 is disposed in 65 spaced parallel relation to each other and the sides 8 and 9 of the frame, and adjacent each other, so that the distance between each member substantially corresponds to the diameter of one of said members. 70

Extending laterally of the frame is a series of expandible and retractable supporting members 14, each of the supporting members 14 consisting of a length of resilient wire coiled at spaced intervals longitudinally 75 thereof, each coil being connected by a bowed connecting portion 15. The end portion 16 of each of the supporting members 14 is secured to the side member 9 of the frame, while the end portion 17 of the supporting member 14 is secured to the side member 8 of the frame. The supporting members 14 are disposed in spaced parallel relation to each other laterally of the frame, the distance between said members corresponding to the diameter of one of said members. These members substantially resemble coil springs. 85

In assembling the supporting members of each frame, the connecting portion 15 of each of the supporting members 14 are extended over the adjacent coiled portions of the adjacent supporting member 11, so that in this way each of the supporting members 11 substantially intersects the adjacent portion of each of the supporting members 14, thereby disposing the coils of the members 14 between the members 11 and permitting the members 14 to intersect the members 11. Thus both the members 11 and 14 are disposed substantially in the same plane within the frame, thereby providing an even surface on which dishes may be placed. 90 95 100

Any number of the frames 5 may be provided, but for the purpose of illustration only two are shown. Each frame is connected to the adjacent frame by a connecting member consisting of a length of resilient wire 18 which is coiled about the side member 8 of one frame and the side member 9 of the adjacent frame, so as to enclose said side members in the connecting 105 110

member. The end 19 of the connecting member is connected to the side member 9 of one frame, while the end 20 of the connecting member is connected to the side member 8 of the adjacent frame. The coils of the connecting member are disposed in the plane of the coils of the supporting members 11 and 14. In this way the connecting member substantially forms a continuation of the mat of each frame thereby preventing the dishes from coming in contact with the sides of the frame.

In Figure 2, another form of the invention is shown. In this form protecting members 21 are provided for the ends of the frame and sides of the frame not connected to the adjacent frame. These protectors are similar to the supporting members 11 and 14 in that they are constructed from a length of wire which is coiled around the sides and ends of the frame and secured to said sides and ends to prevent contact of the dishes with said sides and ends.

With this mat dishes may be placed on the drain board without the exercise of great care, as the flexibility of the supporting members 14 will prevent the dishes from breaking and also prevent the dishes from coming in contact with the drain board, so that cracking of the dishes is impossible. Furthermore, in view of the coiled formation of the supporting members 13 and 14, said members permit the water dripping from the dishes to pass beneath the mat down the drain board to the sink so that the mat serves the additional purpose of a drainer. In addition to this the intersecting fea-

ture of the supporting members 11 and 14 prevents the dishes from moving to any great extent while on the mat, so that the possibility of the dishes sliding off the mat on to the floor is eliminated. By disposing the supporting members in spaced relation to each other and to the supporting members of the adjacent series, sufficient room is provided to permit yielding movement of said members when the dishes are placed thereon. All of these features are possessed by a device that is simple in construction and can be manufactured in large quantities from a small amount of material.

What is claimed is:—

A dish mat comprising a plurality of frames, a connecting member coiled around the adjacent sides of each frame for yieldably and movably connecting said members to each other, each of said frames having a series of longitudinally extending supporting members and a series of laterally extending supporting members, each of the longitudinally extending supporting members consisting of a length of coiled resilient wire, the ends of said wire being fastened to the ends of the frame, each of the laterally extending members consisting of a length of resilient wire coiled at spaced intervals longitudinally thereof, the portions of the wire between the coils being adapted to extend over the coils of the adjacent longitudinal supporting members.

In testimony whereof I hereunto affix my signature.

ALBBERT J. SMILEY.
